UNITED STATES PATENT OFFICE.

HERBERT B. SPERRY AND GUSTAV W. WITTE, OF CHICAGO, ILLINOIS, ASSIGNEES TO
INTERNATIONAL HARVESTER COMPANY, OF CHICAGO, ILLINOIS, A CORPORATION
OF NEW JERSEY.

BUNDLE CARRIER.

Application filed March 1, 1922. Serial No. 540,114.

Our invention relates to bundle carriers for grain harvesters.

Heretofore, considerable difficulty has been experienced in securing a complete discharge of the bundles from the bundle carrier of a harvester when the bundles pile up unevenly thereon or are crowded at the forward end of the carrier which frequently happens when operating on the downward side of a hill in rolling country. Under these conditions some of the sheaves frequently remain on the carrier causing the carrier to operate with difficulty and occasionally necessitating the stopping of the machine to clear the carrier.

This invention has for one of its objects to provide a bundle carrier which, at all times and under all conditions, will deliver the sheaves therefrom onto the ground with their butts in substantial alignment.

A further object is to provide a carrier that will operate efficiently on hillsides and rolling country and will prevent the crowding and lodging of the sheaves on the forward end of the carrier.

A still further object is to provide a carrier which is capable of yielding upwardly and rearwardly when striking an obstacle and, at the same time, will not be tripped or dumped by such obstruction.

These and other objects are attained by providing a construction in which the bundle carrier simultaneously tilts and drops, enabling the carrier to conform to the surface of the ground and in which the sheaves are removed therefrom when the same is in discharging position by contact of the stubbles in the field. In order that my invention may be clearly and fully disclosed, I have illustrated one embodiment which the same may assume in practice in the accompanying drawings in which:

Fig. 1 is a side elevational view of a part of a harvester embodying my improved bundle carrier;

Fig. 2 is a top plan view of the carrier shown in Fig. 1;

Fig. 3 is a detail side elevational view of the carrier showing the same in its normal bundle receiving position (full lines) and its bundle discharging position (dotted lines);

Fig. 4 is an enlarged detail view of the lifting crank and its cooperating parts;

Figs. 5, 6 and 7 are enlarged plan elevational and side elevational views respectively

of the foldable fine supporting member; and

Fig. 8 is an enlarged detail view of the inner connection of the fine supporting member with the frame.

60

The binder shown is of the standard construction including a main frame 10 mounted on the main wheel 11, a supplemental frame member 12 and deck 13 provided with the usual binding attachment 14 having the discharging arms 15 for discharging the sheaves from the binding mechanism of the harvester. As the binder and the mechanism for operating these last named elements are all of the standard construction 65 and per se form no part of the present invention, the same need not be herein more specifically described.

Our improved bundle carrier construction comprises a laterally extending foldable fine supporting member 16. This supporting member 16 is made up in two sections 17 and 18 pivotally connected to each other at 19 for the purpose hereinafter more fully described. The inner or grassward section 70

17 of the foldable supporting member 16 is loosely connected to the main frame 10 through the bracket 20 which is fixed to a main supporting bracket 21 fixed to the main frame 10 by means of bolts 22. The bracket 75

20 is provided with an obliquely extending stud 23 adapted to slidably receive a slotted bracket 24 fixed to the grassward end of the section 17. This connection permits the fine supporting member to swing free in a vertical plane about the stud 23. The main supporting bracket 21 is supported in its position by the supplemental binder frame member 12 by means of diverging braces 25. The main bracket 21 is further provided with a 80

forwardly projecting portion 26 which has formed integrally therewith an upwardly extending arm 27 having an aperture 28 adapted to receive a hook member 29 for connecting a main bearing spring 30 thereto. 85

The stubbleward end of the spring 30 is connected to a link 31 which in turn is connected to an adjustable bolt 32 fixed to the supporting fine member 16. This spring 30 normally maintains the supporting member 90

16 in its elevated and extended position as shown in the full lines in Figs. 1 and 2. Adjacent the upwardly extending arm formed on the main bracket 21 is a socket 105

33 adapted to receive a crank shaft 34. The 110

- crank shaft 34 is held in position by a bracket 35 secured to the side of the socket 33 by means of a bolt 36. The grassward end of the crank shaft 34 is provided with the usual crank end connections to the foot treadle mechanism within easy reach of the operator. This construction just described is not shown as it is a regular standard construction for harvesters.
- 10 The stubbleward end of the crank shaft 34 is provided with a crank arm 37. Pivotedly secured to the crank 37 by means of a cotter and washer 38; is an adjustable connecting link 39 and hook 40 for the purposes hereinafter more fully set forth. In order to allow for variations in manufacture, an adjustment has been provided for adjusting the stop of the crank 37 for locking the same on center by providing a forwardly extending inclined arm 41 provided with an adjustable bolt and nut 42. Pivotedly mounted on the main supporting bracket 21 by means of a bolt 43 is the lifting bracket or crank 44. The rearward end of the crank 44 is securely fixed to the section 17 of the tine supporting member 16 by means of bolts 45. For further securing the section 17 to the crank 44, a braced rod 46 has been provided and is secured by means of a bolt 47 to the upper end of the crank 44. The upper crank arm of the crank 44 is provided with an aperture 48 adapted to pivotally receive the adjustable hook 40. It will be noted from this construction that as the crank shaft 34 is thrown from the full line position shown in Fig. 4 to the dotted line position shown in this figure, that the bundle carrier is dropped or dumped from the full line position to the dotted line position shown in Fig. 3.
- 15 Our improved foldable tine supporting member as above described, comprises the sections 17 and 18. The section 18 is limited in its forward pivotal movement with respect to the section 17 by means of a clip 49 bolted to the section 17 by means of a bolt 50. Adjacent the grassward end of section 18 is an aperture 51 adapted to receive a cotter 52 for the purpose hereinafter set forth. Secured to the stubbleward end of the section 17 by means of a bolt 53 is a Z-shaped bracket 54 having a substantially horizontal arm 55 adapted to pivotally support, by means of a bolt 56, a bracket 57 which is secured to the section 18 by means of rivets 58. The bracket 54 is provided with a forwardly projecting arm 59 having an aperture 60 adapted to register with the aperture 51 for receiving the cotter 52 when the bundle carrier is folded in the position shown in the dotted lines in Fig. 2.
- 20 The bundle carrier proper comprises the longitudinally extending tines 61 of the well known form having a substantially vertical by bent portion 62 extending through the tine supporting member 16. The forward end of the tines 61 are provided with substantially vertical portions which extend through the tie-bar 63. The tines are maintained in their position by the brace-bar 64 secured to the tie-bar 63. The outer rail 65 is secured to the tie bar 63 and brace-bar 64 by means of a bolt 66, and is also secured to the section 18 by means of the bracket 67 and bolt 68. The usual U-shaped tine rail 69 is secured to the side rail 65 by the bracket 67 and the bolt 70. The carrier is also provided with the usual rail rod 71 secured to the cross tie-bar 63. The inner side rail member 72 is rigidly supported in position by the bolt 56 carried by the bracket 54. The forward end of the rail member 72 is secured to the tie-bar 63 and brace-bar 64 by means of the bolt 73. The side rail 72 is held against pivotal movement by means of a hook rod 74 connecting said rail to the upper arm of the crank 44 by means of the bolt 47.
- 25 From this construction it will be seen that the bundle carrier may yield upwardly about its pivot 43 by reason of the slotted connections 23 and 24 with the main frame when the bundle carrier encounters an obstacle. It will also be noted that by reason of my improved foldable tine supporting member, the bundle carrier may yield about the pivoted bolts 19 and 56 permitting the carrier to yield to a position shown in the dotted lines in Fig. 2.
- 30 In considering the operation of the device, let us assume that the parts are shown in their bundle receiving position as shown in Fig. 1 wherein the bundles delivered by the sheave discharging mechanism 15 may fall upon the tines 61. When a sufficient number of bundles has accumulated upon the carrier, the crank 37 is released by suitable means as, for instance, the usual foot pedal and an initial impulse is given to the crank to throw it away from its stop 42 and release the link connection supporting the supporting member 16. The weight of the bundles on the tines 61 will turn the lifting crank 44 about its pivot 43 depressing the supporting member 16 as shown in the dotted lines in Fig. 3. When the supporting member 16 and tines 61 are in this position, the stubble engages the bundles on the carrier and with a rearwardly sweeping effect cleans the sheaves from the tines speedily and entirely. As soon as the carrier has been emptied of the sheaves, the spring 30 will return the same to its normal position. The single spring operates normally to retain the foldable supporting member in its laterally extending position and at the same time maintains the carrier in its normal bundle receiving position. When it is desired to transport the harvester, the carrier may be folded to the position shown in the dotted lines in Fig. 1 and the cotter 52 may be inserted
- 35 40 45 50 55 60 65 70 75 80 85 90 95 100 105 110 115 120 125 130

in the registering apertures 51 and 60 maintaining the carrier in its folded position.

While we have in this application specifically described one embodiment of our invention, it is of course to be understood that this form of the same is used for the purpose of illustration and that various other constructions may be employed without departing from the spirit of the invention, 10 it being our intention to include all such modifications within the scope of the appended claims.

We claim:

1. In combination, a frame, a bracket pivoted to said frame and having upwardly and rearwardly diverging arms, a bundle carrier including a support connected to the end of the rearwardly diverging arm of said bracket and supported thereby, and control means 20 connected to the upwardly diverging arm for controlling the pivotal movement of the bracket to effect movement of the support for dumping the bundle carrier.

2. In combination, a frame, a bracket 25 rockably mounted on the frame and embodying upwardly and rearwardly extending diverging arms, a supporting member connected at its inner end to the frame and intermediately of its ends supported by the rearwardly extending arm of the bracket, a bundle carrier mounted on the supporting member, and means for actuating the carrier.

3. In combination, a frame, a horizontally disposed foldable supporting member 35 mounted on the frame, a bundle carrier carried by the outer end of the member, and means intermediately of the ends of the supporting member for permitting the outer end of the member to swing inwardly with respect to the frame in a horizontal plane to 40 fold the carrier.

4. In a bundle carrier attachment for har- 45 vesters, the combination of a frame, a laterally extending support pivoted to the frame, a hinge intermediate the ends of said support, a bundle carrier mounted on the support at its outer end beyond the hinge, the hinge permitting inward folding of the carrier in a horizontal plane, and means for locking the carrier in such folded position.

5. In a bundle carrier attachment for har- 55 vesters, the combination of a frame, a bracket pivoted to said frame, a supporting member foldable intermediately of its end pivoted to the frame and fixed to the bracket, a bundle carrier mounted on the supporting member at its outer end, means permitting inward folding of the carrier and support, and means for tripping the bracket and dumping the carrier without folding the supporting member.

6. In combination, a frame, a supporting member having a hinge intermediate its ends mounted on said frame, and a bundle carrier carried by said member at its outer

end, said hinge permitting said supporting member to yield in a horizontal plane inwardly toward the frame when said bundle carrier encounters an obstruction.

7. In a bundle carrier attachment for har- 70 vesters, the combination of a frame, a laterally extending support mounted on the frame and having a bundle carrier carried by the member at its outer end, and means permitting the entire support to yield upwardly 75 and a hinge permitting the outer end of the support to fold inwardly when the carrier strikes an obstruction.

8. In a bundle carrier attachment for har- 80 vesters, the combination of a frame, a laterally extending support mounted on the frame and having a hinge intermediately of its ends, a bundle carrier on the outer end of the support, the hinge permitting the carrier to fold inwardly alongside the frame in 85 a horizontal plane, and means for normally maintaining the outer end of the support in a laterally extended position.

9. In a bundle carrier attachment for har- 90 vesters, the combination of a frame, a laterally extending support carried by the frame and comprising a pair of movable sections, a bundle carrier carried by the outer section, means for permitting the outer section to fold rearwardly in an inward direction in a 95 horizontal plane, means permitting the sections as a laterally extending unit to move upwardly to float over obstructions, and means for permitting the sections as a laterally extending unit to drop bodily down- 100 wardly to discharge the carrier.

10. In combination, a frame, a supporting member loosely pivoted to said frame for movement in substantially a vertical plane, said supporting member being formed of a 105 plurality of sections pivoted together, and means for permitting one of said sections to yield with respect to the other in substantially a horizontal plane.

11. In a bundle carrier attachment for 110 harvesters, the combination of a frame, a laterally extending bundle carrier support connected to the frame for a dropping movement in a plane at right angles to the line of draft of the harvester, a two armed lever pivoted to the frame, the support being carried intermediately of its end by one arm of the lever, and control means for effecting dropping movement of the support connected to the other arm of the lever. 115

12. In a bundle carrier attachment for harvesters, the combination of a frame, a laterally extending bundle carrier support carried at one end on said frame for bodily dropping movement in a plane at right angles to the line of draft of the harvester, a two armed lever pivoted to the frame, a connection between one arm only of said lever and the support, and means connected to the other arm of the lever for controlling 125 130

pivotal movement of the lever to effect dropping of the support.

13. In combination, a frame, a substantially triangular bracket having its apex pivoted on the frame, a bundle carrier including a support connected to another angle of the bracket, and control means connected to the

remaining angle of the bracket for turning the bracket on its pivot to drop the support for dumping the bundle carrier.

10
